TROUSER CUFF AND METHOD OF FASTENING SAME

Charles B. Goodstein, New York, N. Y.

Application February 15, 1937, Serial No. 125,777

12 Claims. (Cl. 2—232)

This invention relates to methods of fastening together layers of flexible sheet material such as textile fabrics. It is particularly directed to trouser cuffs and methods of fastening the trouser cuff in place on the trouser leg.

An object of this invention is to provide a highly improved method for clipping or stapling together layers of flexible sheet material, for example, a trouser cuff, to the trouser leg, without exposing any portion of the clip or staple from the outside of the trouser leg.

A further object of this invention is to provide a highly improved method of the character described, wherein the staple engages the fibers of the outer fold of the cuff without piercing said outer fold, whereby the staple is hidden from view when the trouser is worn.

A further object of this invention is to provide a trouser cuff having highly improved fastener means for holding the cuff in place, and including a staple engaging the fibers of the outer fold of the cuff without piercing the cuff, and being further provided with hooked ends adapted to become embedded in the cuff to prevent the fastener from accidentally loosening.

A further object of this invention is to provide highly improved, durable apparatus for fastening the trouser cuff in place, in accordance with my invention, which shall be easy to manipulate without necessity for exceptional skill or training.

Yet another object of this invention is to provide a simple and economical improved process of the character described, which shall be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front, elevational view of the inside of a portion of the bottom of a trouser leg and illustrating the invention;

Fig. 2 is a side, elevational view of apparatus embodying the invention, for carrying out my improved process;

Fig. 3 is an enlarged, elevational, cross-sectional view of a portion of the apparatus shown

in Fig. 2, with the parts in position after the stapling operation has been accomplished;

Fig. 4 is a cross-sectional view taken on line 4—4 of Fig. 3;

Fig. 5 is a top plan view of my improved apparatus with the trouser leg in position for the stapling operation, and taken along lines 5—5 of Fig. 3; and

Fig. 6 is a cross-sectional view taken on line 6—6 of Fig. 1.

Referring now in detail to the drawing, 10 designates a portion of a trouser leg provided with a cuff 11 of usual construction. The cuff 11, as shown in the drawing, comprises a fold 12, extending upwardly from the lower end of the 15 bottom of the trouser leg. Extending downwardly from the upper end of the inner fold 12 is an outer fold 13, forming a folded upper edge 11a, and terminating in an upwardly folded hem portion 15 contacting the inner surface 16 of the 20 trouser leg and stitched thereto in the usual manner.

Trouser cuffs are usually stitched to the trouser legs to hold the cuffs in place. When the trousers are sent to dry cleaners or laundries, 25 the stitching is usually severed so that the cuff may be folded down to facilitate the cleaning or laundering operation. After the cleaning operation, the cuff is folded back into original position. To save labor and expense of restitching, 30 the trouser cuffs may be easily and economically attached to the trouser leg in accordance with my improved method and with my improved apparatus, as will appear hereinafter.

As shown in the drawing, the trouser cuff 11 is fastened to the trouser leg 10 by a staple 20. 35 The staple 20 has a crown portion 21 disposed at the inner surface of the trouser leg. Extending from the crown portion 21 are prongs or legs 22 extending through the trouser leg 10 through the inner fold 12 and engaging the fibers of the outer fold 13 without piercing the latter. The legs 22 pierce the trouser leg 10 and the inner fold 12 twice, going in and coming out, as shown in the drawing. Extending from the legs 22 are hooked or curved portions 23 exposed at the inner surface 16 of the trouser leg. Said hooked portions 23 extend inwardly toward each other and are inclined away from the plane of the legs 22, to again pierce or become embedded in the trouser leg 10, as indicated at 24. It will be noted that the legs 22 are bent or curved when the cuff is straightened out, as shown in Fig. 6 of the drawing, and that the piercing ends 24 of the staple are pointed.

The manner of carrying out the stapling operation, and one form of apparatus on which the same may be carried out, will now be described. The apparatus 30 for carrying out my improved process comprises a support or stand 31 on which is mounted one leg 32 of a desk type stapling machine. On the leg 32 is the anvil 33, provided with a pair of similar, symmetrically disposed, diverging grooves 34 of curved, vertical cross-section. Pivoted to the leg 32 is the staple housing 36, provided with a usual plunger housing 37, on which is slidably mounted the usual plunger 38 for driving the staples. The plunger 38 is maintained in raised position by the usual compression spring 39, interposed between the housing 37 and the head of the plunger. To normally maintain the casing 36 in raised position, a compression spring 40 is interposed between an abutment 41 on the staple housing, and an abutment 42 on the leg 32.

Slidably mounted on the support 31, is a member 50 comprising a horizontal rod 51 slidably received in an opening or socket 52 formed in said support. A pin 62 on said rod passes through a horizontal slot 62a in said support, to prevent rotation and to limit sliding movement thereof. Interposed between said rod 51 and the rear end of said socket 52 is a coil compression spring 61. A pin 63 on rod 51 is adapted to contact the front of the support to limit inward movement thereof to a predetermined position. Attached to the front end of rod 51 by screws 54 is an angle-shaped plate having a vertical wall 55 and a rearwardly extending horizontal wall 56 provided with a thickened, rounded, extending tongue 57. The tongue 57 has a longitudinal, recessed, vertical surface 60 aligned with the anvil 33, for the purpose hereinafter appearing.

To carry out my improved process, the cuff of the trouser leg is bent or folded around the tongue 57 in the manner disclosed in Figs. 2 and 3 of the drawing, with the main portion of the cuff disposed beneath the tongue, and the outer fold 13 in contact therewith. The lower edge 10a of the trouser cuff is disposed adjacent the portion 55 of the member 50. The upper edge 11a of the trouser cuff is disposed above the tongue 57.

The operator holds the cuff in the position of Fig. 2 and then pushes member 50 inwardly to the position shown in Fig. 3. By then operating a foot pedal, the rod 70 is pushed up to rotate the lever 71 and depress housing 36 until the stop 72 on leg 33 is contacted to hold the housing in horizontal position in engagement with the trouser leg. Further pressure on the pedal thereafter depresses the plunger 38 against the pressure of the spring 39 for pressing the staple blank through the folded trouser cuff. The bottom ends of the legs of the staple engaging within the grooves 34 are curved or hooked inwardly and to one side of the plane of the staple.

The member 50 is so positioned during the stapling operation (due to contact of pins 63 with the support) that the staple will pierce the trouser leg 10, and the inner fold 12 twice, going in and coming out, and will engage the fibers of the outer fold 13 without piercing through the same. Preferably the recess 60 in the tongue 57 prevents the material of the inner fold 13 from being excessively taut where the legs of the staple pass through or engage the fibers thereof. I preferably use staples having relatively long legs, pointed, chiseled or ground at the ends, as with such staples, the fibers of the outer fold are more easily engaged, the ends of the staples are more readily

curved in the anvil, and straightening of the stapled cuffs is facilitated.

After the stapling operation, foot pressure is removed from the foot pedal and the member 36 is raised by the spring 40. Member 50 is released and moves under action of spring 61. The trouser leg may then be removed from the member 50 and straightened out. Upon straightening the trouser cuff, the legs 22 of the staple will bend or curve into the position shown in Fig. 6 and the ends of the hooked portions of the staple will become embedded in the trouser leg and the cuff will be securely fastened to the trouser leg.

It will be noted that in the stapling operation the legs or prongs do not clinch the fabric, clinching action being prevented by the stop 72. Clinching is avoided to permit the trouser leg to be straightened out after stapling. The stop 72, furthermore, prevents the stapling machine from compressing or distorting the folded trouser cuff, said housing being held at a predetermined position above the tongue 57 by said stop.

Although my improved process has been illustrated and described in particular relation to the fastening of a trouser cuff to a trouser leg, it will be understood that other layers of flexible sheet material, such as textile fabrics, may be fastened together in accordance with my improved method, one dominant feature of the invention being the steps of folding over superimposed layers, driving the staple through the folded layers adjacent the fold, hooking the ends of the staple legs or prongs, and straightening out the stapled layers after the stapling operation.

My improved method may be carried out on stapling machines or apparatus other than that shown in the drawing and described hereinabove, since the stapling operation may be carried out on an ordinary stapler with the provision of means to hold the trouser cuff in folded position and in predetermined relation to the anvil, and stop means for the staple housing to prevent clinching whereby sufficient play is allowed to permit the trouser leg and cuff to be straightened out after stapling.

Although the invention has been described in reference to a pronged staple, it will be understood that a pin may be employed for carrying out my improved process. One end of the pin may be headed and the other end hooked by a stapling machine or both ends of the pin could be hooked or bent after piercing the folded fabric.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A plurality of superimposed layers of flexible sheets, and means for fastening said sheets together, comprising a staple having a crown at the outer surface of an outer sheet, legs having pointed ends piercing said outer sheet and at least one other sheet, going in and coming out, the ends of said legs being hooked back into U-shape to point toward the crown at the outer surface of said outer sheet, and being embedded in said outer sheet.

2. A method of fastening a trouser cuff to a trouser leg consisting in folding the trouser cuff and leg with the outer fold of the trouser cuff on the inside and the trouser leg on the outside, then driving the prongs of a staple through the folded trouser cuff and leg, adjacent the fold, so that the prongs pierce through the trouser leg and through the inner fold of the trouser cuff, twice, going in and coming out, hooking the outer ends of the prongs on an anvil after the prongs have pierced through the trouser leg and inner fold of the cuff, and then straightening out the stapled cuff and trouser leg.

3. In combination with a trouser leg and a cuff at one end of the trouser leg, including inner and outer layers of fabric connected at their upper edges, means for fastening the cuff to the leg, comprising a staple having prongs passing through the trouser leg, inner layer of the cuff, and through some of the fibers of the outer layer without piercing the same.

4. A method of fastening to a trouser leg, a cuff including inner and outer layers of fabric, connected at their upper edges, consisting in folding the trouser leg and cuff, passing the prongs of a staple through the folded trouser leg and inner layer of fabric, going in and coming out, and through some of the fibers of the outer layer of fabric without piercing through said outer layer, hooking the ends of the prongs on an anvil after the prongs have pierced through the folded trouser leg and cuff, at the inner side of the trouser leg, and then straightening out the folded and stapled trouser leg and cuff, whereby the crown and the hooked ends of the prongs are located at the inside of the trouser leg, and the staple is completely hidden from view from the outside.

5. A method of fastening to a trouser leg, a trouser cuff including inner and outer layers of fabric connected at their upper edges, consisting in folding the trouser leg and cuff together, passing the prongs of a staple adjacent the fold, through the folded trouser leg and inner layer of fabric, going in and coming out, forcing the ends of the prongs of the staple after the prongs have pierced the trouser leg and inner layer, twice, against an anvil to bend said ends at the inner side of the trouser leg toward each other and out of the plane of the prongs toward the trouser leg, and then straightening out the folded and stapled trouser leg and cuff, whereby the points of the bent portions of the prongs become embedded in the trouser leg, and the staple is completely hidden from view from the outside.

6. A method of fastening to a trouser leg, a cuff including inner and outer layers of fabric connected at their upper edges, consisting in folding the trouser leg and cuff together, passing the prongs of a staple, through the folded trouser leg and inner layer of fabric, going in and coming out, adjacent the fold, and through some of the fibers of the outer layer without piercing through said outer layer, forcing the ends of the prongs of the staple after the prongs have pierced the trouser leg and inner layer twice against an anvil to bend said ends at the inner side of the trouser leg toward each other and out of the plane of the prongs toward the trouser leg, and then straightening out the folded and stapled trouser leg and cuff, whereby the points

of the bent portions of the prongs become embedded in the trouser leg.

7. A trouser leg having at its lower end a cuff including inner and outer layers of fabric, a staple having its crown on the inner side of the trouser leg and having bendable legs passing through the fabric of the trouser leg and the inner layer of the trouser cuff, going in and coming out, and the ends of the legs of the staple being hooked back into U-shape to point toward the crown, at the inner side of the trouser leg and embedded in said trouser leg, said legs of said staple being curved longitudinally and said trouser leg and cuff being straight.

8. A trouser leg having at its lower end a cuff including inner and outer layers of fabric, a staple having its crown on the inner side of the trouser leg and having its legs passing through the fabric of the trouser leg and the inner layer of the trouser cuff, going in and coming out, and the ends of the legs of the staple being hooked at the inner side of the trouser leg, the legs of said staple engaging the fibers of the outer layer of the trouser cuff without piercing through the same.

9. A trouser leg having at its lower end a cuff including inner and outer layers of fabric, a staple having its crown on the inner side of the trouser leg and having its legs passing through the fabric of the trouser leg and the inner layer of the trouser cuff, going in and coming out, and the ends of the legs of the staple being hooked at the inner side of the trouser leg, the hooked ends of said staple being bent out of the plane of the legs toward the trouser leg and being embedded in said trouser leg.

10. A trouser leg having at its lower end a cuff including inner and outer layers of fabric, a staple having its crown on the inner side of the trouser leg and having its legs passing through the fabric of the trouser leg and the inner layer of the trouser cuff, going in and coming out, and the ends of the legs of the staple being hooked at the inner side of the trouser leg, the legs of said staple engaging the fibers of the outer layer of the trouser cuff without piercing through the same, the hooked ends of said staple being bent out of the plane of the legs of the staple toward the trouser leg and being embedded therein.

11. In combination with a trouser leg having a cuff at the bottom end thereof, comprising inner and outer layers, means for fastening the cuff to the trouser leg, comprising a fastener of bendable metal, having a longitudinally bent portion piercing the trouser leg, the inner layer of the trouser cuff and engaging the fibers of the outer layer of the trouser cuff without piercing through said outer layer.

12. A method of fastening a trouser cuff to a trouser leg, consisting in folding the trouser cuff and leg with the outer fold of the trouser cuff on the inside and the trouser leg on the outside, then driving a fastening member through the folded trouser cuff and leg, adjacent the fold, to pierce through the trouser leg and through the inner fold of the trouser cuff, going in and coming out, and hooking one end of said member on an anvil, after said member has pierced through said trouser leg and inner fold of the cuff, and then straightening out the stapled cuff and trouser leg.

CHARLES B. GOODSTEIN.
